DESIGN FOR A PENDENT LIGHTING FIXTURE

Leroy C. Doane, Meriden, Conn., assignor to The Doane Products Corporation, Meriden, Conn., a corporation of Connecticut

Application July 31, 1940, Serial No. 94,066

Term of patent 7 years

To all whom it may concern:

Be it known that I, Leroy C. Doane, a citizen of the United States of America and a resident of Meriden, in the county of New Haven and State of Connecticut, have invented a new, original, and ornamental Design for a Pendent Lighting Fixture, of which the following is a specification, reference being had to the accompanying drawing forming a part thereof.

The single figure in the drawing is a perspective view of a pendent lighting fixture showing my new design.

I claim:

The ornamental design for a pendent lighting fixture, as shown.

LEROY C. DOANE.
